ELECTRICAL OUTLET PANEL

Richard E. Abendroth, 11021 36th Ave. N.,
Minneapolis, Minn.

Filed June 7, 1962, Ser. No. 70,463

Term of patent 14 years

(Cl. D26—1)

FIG. 1

FIG. 2

FIG. 3

FIG. 4

FIG. 5

FIG. 6

FIG. 7

FIG. 8

FIG. 1 is a view in perspective of an electrical outlet panel, showing my design;

FIG. 2 is a view in side elevation, as seen from the opposite side of FIG. 1;

FIG. 3 is a view in end elevation as seen from the end opposite to that shown in FIG. 1;

FIG. 4 is a view in end elevation as seen from the end shown in FIG. 1;

FIG. 5 is a view in top plan;

FIG. 6 is a view in side elevation, illustrating the side shown in FIG. 1;

FIG. 7 is a view in bottom plan; and

FIG. 8 is a view corresponding to FIG. 1 but showing a plug removed from a receptacle in the panel, on a reduced scale.

I claim:

The ornamental design for an electrical outlet panel, as shown.
